UNITED STATES PATENT OFFICE.

CHARLES F. LEE, OF ASTORIA, ILLINOIS, ASSIGNOR OF ONE-HALF TO
JOHN B. HARRIS, OF ASTORIA, ILLINOIS.

MANURE-SPREADER.

No. 820,653.

Specification of Letters Patent.

Patented May 15, 1906.

Application filed October 11, 1905. Serial No. 282,294.

To all whom it may concern:

Be it known that I, CHARLES F. LEE, a citizen of the United States, residing at Astoria, in the county of Fulton and State of Illinois, have invented a new and useful Manure-Spreader, of which the following is a specification.

This invention relates to manure-spreaders, and among the principal objects of the invention are the promotion of simplicity, durability, and general efficiency in the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be made when desired.

In the drawings, Figure 1 is a top plan view of the improved fertilizer-distributer. Fig. 2 is a longitudinal vertical sectional view taken on the plane indicated by the line 2-2 in Fig. 1. Fig. 3 is a sectional view, enlarged, taken through the driving means for the distributing-cylinder. Fig. 4 is a side elevation, enlarged and partly in section, illustrating the feeding mechanism.

Corresponding parts in the several figures are indicated throughout by similar characters of reference.

The improved manure-spreader of the present invention comprises a specially-constructed wagon-box which may be mounted for operation upon the running-gear of any ordinary farm-wagon, thus reducing the initial cost of the device and producing a device which requires much less room for storage than a device of this class mounted upon its own running-gear.

In the several figures of the drawings, A designates a box or receptacle which is of the general shape and outline of an ordinary wagon-box, comprising the side members 1 1 and the front member 2. The side members

1 1 are provided upon their inner sides near 55 their lower edges with bottom supporting flanges 3, connected by cross-braces 4 4, which in turn are connected by a longitudinal brace 5. Beneath the flanges 3 3 are auxiliary flanges 6, serving to support the lower 60 lead of the flexible bottom while the box is being unloaded. The flanges 3 are mutilated at intervals for the accommodation of rollers 7.

The bottom B of the receptacle is composed of a plurality of transverse strips 8 8, 65 secured upon and connected by flexible members, such as straps 9, the ends of which are connected by chains 10, passing over sprocket-wheels 11 upon a shaft 12, supported for rotation at the front end of the box. The flexible members and chains of the bottom are also guided over guide-rollers 13 upon a shaft 14 near the rear end of the box. The side members of the latter are also provided with bearings for a guide-roller 15, which supports the 70 lower lead of the flexible connecting members of the bottom and guides the strips of which the latter is composed onto the supporting-flanges 6.

The box or receptacle A is provided with a 75 front bolster 16, which is spaced beneath the side members 1 1 by means of blocks 17, so as not to interfere with the operation of the flexible bottom and related parts. This bolster is provided with stakes 18 adjacent to 80 the sides of the box or receptacle, and when the box is mounted upon a running-gear in position for operation the bolster 16 is supported upon the front bolster of such running-gear so that the box or receptacle of the 85 present invention will be somewhat tilted in a downward and rearward direction to facilitate the discharge of the load. The side members of the device are also provided upon their under sides with shouldered blocks 19, 90 95 adapted to engage the rear bolster of the running-gear, as will be seen in Fig. 2 of the drawings.

The flexible bottom B is provided at its 100 forward extremity with an upstanding shield 20, forming a movable front closure to confine the contents of the receptacle while the latter is being unloaded. A movable tail-gate 21 is also provided, said tail-gate being provided with cleats 21', pivotally engaging 105 the crank 25 of a crank-shaft 22, which latter is mounted in bearings 23 upon the upper edges of the side members 1 1 of the box or

receptacle. One end of the crank-shaft is provided with an auxiliary crank 24, which is formed at an angle to the tail-gate-supporting crank 25, the side members of the latter when the gate is in a closed position being accommodated in recesses 26 upon the inner sides of the side members 1, while the crank 24 extends above the upper edges of said side members. The means for operating the adjustable tail-gate will be presently more fully described.

The side members 1 1 of the box or receptacle are provided near their rear ends with bearings for the shaft 27 of a distributing-cylinder 28, which is provided with radially-extending teeth 29. The shaft 27 carries a pinion 30, meshing with a spur-wheel 31 upon a shaft 32, which also carries a sprocket-wheel 33, driven by means of a chain 34 from a sprocket-wheel 35, which is clamped detachably upon one of the hind wheels of the running-gear upon which the device is mounted for operation. The gearing will obviously be made of such proportions as to cause the distributing-cylinder to be rotated at any desired speed.

The shaft 32, which carries the spur-wheel 31 and the sprocket-wheel 33, is supported in a suitable bracket or bearing 36. The spur-wheel 31 is fast upon the shaft, and the hub thereof is provided with a clutch member 37, adapted to be engaged by a clutch member 38 upon the hub of the sprocket-wheel 33, which latter is loose upon the shaft and is normally forced in the direction of the spur-wheel by the action of a spring 39. The hub of the sprocket-wheel has a collar 40, between which and the supporting-bracket 36 is interposed a slotted slide 41, the engaging portion of which is wedge-shaped, as shown at 42 in Fig. 1 of the drawings, so that by driving the wedge-shaped slide between the collar of the sprocket-wheel and the bearing the former will be pushed outward against the tension of the spring 39, and the clutch members 37 and 38 will become disengaged, so that sprocket-wheel 33 will rotate idly upon the shaft 32.

The upper end of the slide 41 is connected pivotally with the crank 24, and the slide 41 is connected pivotally at an intermediate point with the rear end of a link or connecting-rod 43, the front end of which is pivotally connected with one end of a bent lever 44, which is pivoted upon one side of the box or receptacle near the front end of the latter, so as to be capable of being readily manipulated by the driver or operator. The latter by manipulating the lever 44 may pull the slide 41 in a forward direction, thus permitting the spring 39 to move the sprocket-wheel 33 until the clutch members 38 and 37 are in engagement. By the same operation the upper end of the slide 41 will oscillate the crank-shaft carrying the tail-gate 21, thus causing

said gate to be elevated to the position shown in dotted lines in Fig. 2 of the drawings, in which position it is elevated above the load and is capable of swinging freely, so as not to interfere with the unloading operation. By operating the lever 44 in the opposite direction the wedge-shaped slide will be driven forwardly between the collar of the sprocket-wheel 33 and the bearing 36, thus throwing the driving mechanism for the distributing-cylinder out of gear.

For the purpose of operating the flexible movable bottom member of the device the shaft 12 is provided with a ratchet-wheel 45 and with a pawl 46, having side members 47 straddling the ratchet-wheel and provided with slots 48, slidably engaging the shaft. It will be observed that when the pawl member is rocked in one direction it will ride over the ratchets 49 of the wheel 45, while by rocking the pawl member in the opposite direction the ratchet-wheel will be rotated to the extent of one or more teeth or ratchets, according to the extent of the oscillatory movement of the pawl. The latter is provided with an upward-extending arm 50, having a plurality of apertures 51, any one of which is adapted for pivotal engagement with a link-rod 52, terminating in a loop or strap 53, engaging an eccentric disk 54 upon a shaft 55. The latter carries a sprocket-wheel 56, which is connected by a chain 57 with one of the units or members of a cone-sprocket 58, which is clamped detachably upon one of the hind wheels of the running-gear in connection with which the invention is used. By using a cone-sprocket, as shown, the invention may be successfully applied to and used in connection with running-gears having transporting-wheels of various sizes or diameters.

Supported pivotally in one of the side members 1 of the box or receptacle is a shaft 60, having at its outer end a crank 61 and at its inner end an arm 62, which latter is located in the path of the lower lead of the flexible bottom member of the device. The crank 61 is connected by a retracting-spring with a fixed point, whereby said crank is normally held in contact with a pin or stud 63, the spring 64 exerting its tension upon the crank to hold the free end of the latter in a lowered position and out of engagement with the link-rod 52, while the arm 62 is located in the path of the movable bottom in the position shown in Fig. 4 of the drawings. When the arm 62 is struck by the movable bottom, and thereby moved in the direction of the arrow in Fig. 4, the shaft 60 will be oscillated until the tension of the spring 64 may be exerted to turn it until the crank 61 strikes the under side of the link-rod 52, thus elevating the latter and the pawl member connected therewith until said pawl member is supported out of possible engagement with the

ratchet-wheel 45, the pawl member being sustained in inoperative position without regard to the movement of the link-rod 52, which latter when reciprocated will ride idly upon the crank 61.

A lever 66, which is fulcrumed upon one side of the receptacle, is bifurcated at its lower end, as shown at 67, to engage the crank 61, which may thus be operated by the driver or operator whenever it shall be desired to stop the operation of the feed mechanism prior to the discharge of the entire load.

One extremity of the shaft 12 is squared for the reception of a crank-handle 68, whereby it may be rotated for the purpose of restoring the bottom of the device to load-receiving position after a load has been discharged.

In the operation of this invention the shaft 12 is rotated until the front end of the bottom B is moved to a point at which the shield or gate 20 lies in contact with the front gate 2. The load-receiving portion of the bottom is now supported upon the flanges 3 and upon the framework 4 and 5, which is of sufficient strength to support the load which may be piled upon the bottom. While the box or receptacle is being loaded the movable tail-gate is in the position shown in Fig. 2 of the drawings in full lines, it being also understood that when the tail-gate is in this position the driving-gear of the distributing-cylinder is thrown out of operation by the wedge-shaped slide 41. While the wagon is being loaded and while it is being driven to the field where the manure is to be spread the shaft 60 is turned to a position in which the crank 61 will support the link 52 in a raised position, thus holding the pawl 46 out of engagement with the ratchet-wheel 45. When loaded, the device may be driven to the point of discharge, after which the lever 44 is manipulated to swing the tail-gate to an unobstructing position the slide 41 being simultaneously withdrawn to a position at which the clutch members 37 and 38 may engage each other, thus causing motion to be transmitted from one of the transporting-wheels 50 of the running-gear to the distributing-cylinder, which latter as it rotates loosens the fertilizing material and scatters it over the ground, it being understood that the lever 66 is simultaneously operated to oscillate the shaft 60 and to place the crank 61 in the position shown in Fig. 4, where it will not interfere with the operation of the link-rod 52 and the feed-pawl 46, whereby the shaft 12 will be slowly rotated to move the bottom and the load supported thereon in a rearward direction to be disposed of by the distributing-cylinder. The feed movement may be regulated, as hereinbefore described, by connecting the link-rod 52 with the arm 50 of the

pawl member at various distances from the shaft upon which the pawl member rocks. As already stated, the feed mechanism may be thrown out of gear at any moment by means of the lever 66, but it will be thrown automatically out of gear by the lower lead 70 of the bottom contacting with the arm 62 when the load is discharged, thereby avoiding possibility of straining or breaking the feed mechanism.

Having thus described the invention, what is claimed is—

1. In a manure-spreader, a receptacle, supporting-flanges upon said receptacle, a flexible bottom, supporting means for the same, a front bolster connected permanently with 80 the receptacle and spaced from the under edges of the side members of the receptacle and shouldered blocks secured upon the under edges of the side members and adapted to engage the rear bolster of a running-gear. 85

2. In a manure-spreader having a traveling bottom, a shaft having a crank, a tail-gate suspended upon said crank, an auxiliary crank extending from the crank-shaft at an angle to the gate-supporting crank, an operating-lever, and a link-rod connected with said lever; in combination with a movable member connecting the end of the link-rod with the auxiliary crank.

3. In a manure-spreader having a traveling bottom, a distributing-cylinder supported for rotation, driving means for said cylinder including a pair of clutch members, a slideable wedge member movable between the clutch members, a shaft having a crank, a tail-gate supported upon said crank, an auxiliary crank upon said shaft having pivotal connection with the slideable wedge member, an operating-lever, and a link connecting said lever with the slideable wedge member to 105 simultaneously operate said wedge and the crank-shaft with which it is connected.

4. In a manure-spreader, a traveling bottom including endless flexible members, supporting-shafts for the endless members, a ratchet-wheel on one of the supporting-shafts, a gravity-pawl slidably engaging the shaft and the ratchet-wheel, an eccentric-rod connected with the pawl, a shaft having a crank adapted to engage the eccentric-rod to 115 elevate the pawl from engagement with the ratchet, spring means for holding the crank out of engagement with the eccentric-rod, and an arm extending from the crank-shaft in the path of the lower lead of the traveling 120 bottom.

In testimony that I claim the foregoing as my own I have hereto affixed my signature in the presence of two witnesses.

CHARLES F. LEE.
